UNITED STATES PATENT OFFICE.

MELVILLE TANNENHOLZ, OF BROOKLYN, NEW YORK.

DESIGN FOR A LUNCHEON MAT FOR HOT PLATES.

Application filed April 6, 1927. Serial No. 21,487. Term of patent 3½ years.

To all whom it may concern:

Be it known that I, MELVILLE TANNENHOLZ, a citizen of the United States of America, residing at Brooklyn, in the county of Kings and State of New York, have invented a new, original, and ornamental Design for a Luncheon Mat for Hot Plates, of which the following is a specification, reference being had to the accompanying drawing, forming part thereof.

Figure 1 is a plan view of a luncheon mat for hot plate showing my new design; and Figure 2 is an edge view of the same.

I claim:—

The ornamental design for a luncheon mat for hot plates, as shown.

In testimony whereof I affix my signature.

MELVILLE TANNENHOLZ.
